Isaac. Stead.

UNITED STATES PATENT OFFICE.

ISAAC STEAD, OF PHILADELPHIA, PENNSYLVANIA.

IMPROVEMENT IN CONDENSING CARDING-ENGINES.

Specification forming part of Letters Patent No. 35,114, dated April 29, 1863.

To all whom it may concern:

Be it known that I, ISAAC STEAD, of Philadelphia, in the county of Philadelphia and State of Pennsylvania, have invented some new and useful Improvements in Condensing Carding-Engines for Carding and Condensing Fibrous Substances; and I do hereby declare that the following is a full, clear, and exact description of the construction and operation of the same, reference being had to the annexed drawings, making a part of this specification, in which—

Figure 1 is a side view; Fig. 2, an end view. Fig. 3 is an enlarged section of doffer-shaft and traversing-cam. Figs. 4 and 6 are enlarged sections of the revolving toothed fiber-separator. Fig. 5 is an enlarged section of the collar-doffing roller.

My improvements belong to that class of cards called "condensers."

To enable others skilled in the art to make and use my invention, I will proceed to describe its construction and operation by referring to the accompanying drawings.

A is the cylinder, and C the frame, which are made in the ordinary manner.

B is the doffer, which I propose to make larger than the usual size. For a forty-eight-inch cylinder I use a thirty-six-inch-diameter doffer, the doffer being thirty-six inches wide on the face and covered with a continuous piece of wire fillet. I now divide the face of the doffer into seventy-two parts, (two to the inch,) or as seen in Fig. 2, which is divided into twenty-four parts. The cylinder delivers the fibers to the doffer, covering the whole face. It is necessary that the fibers should be separated at the points where the wire is divided. I do this by the revolving toothed fiber-separator I, which is constructed as seen in Fig. 6.

M is a shaft turned to fit the holes in the collars N N and circular plates L. At I the collar is forged fast and turned true. One of the circular plates is slipped on against the collar, and then one of the collars N turned to suit the width of the rings or divisions on the doffer; then a second circular plate, and so on, till you have as many circular plates as you have rings on the doffer. The whole is firmly fastened by the last collar, which has

a thread cut in it and a corresponding thread cut on the end of the shaft. The last collar acts as a nut and the whole is screwed tight. The circular plates can be made of sheet-steel about one-sixteenth of an inch in thickness. The teeth should be about eight to the inch of circumference.

The fiber-separator is hung in bearings in the plate R, Fig. 1. This plate is hung on the doffer-shaft and steadied by the pins a a a. The fiber-separator is set so that the saws or plates will pass between the rings on the doffer and separate the fibers. All the fibers that the separator takes from the doffer are collected by the stripper S, as seen in Fig. 1, and carried back to the cylinder. The stripper is a plain roller covered with wire fillet and set so as to work between the fiber-separator and cylinder.

Having described the construction and operation of the fiber-separator, I will now describe the construction of the collar-doffing roller K, as seen in Figs. 2 and (section) 5.

I make a plain shaft, as seen in Fig. 5. The collars o o o are made to fit tight on the shaft K. By referring to Fig. 2 it will be seen that I have four rollers and six collars on each roller or shaft. The collars o o o can be made of wood and covered with cloth, or they may be made of metal, leather, or india-rubber. To operate my doffing-roller on a thirty-six-inch wide doffer with seventy-two rings or divisions, I make the collars one-half-inch wide and eighteen collars on each roller or shaft. I set them as seen in Fig. 2. The first collar to the left on the bottom roller takes the slubbing off of the first ring on the left of the doffer, and the first collar on the next roller above the slubbing off of the second ring, and the first collar on the third roller the slubbing off of the third ring, and the first collar on the fourth roller the slubbing off of the fourth ring, and the second collar on the bottom roller the slubbing off of the fifth ring or division of the doffer, and so on, as seen in Fig. 2. The doffing-rollers deliver the slubbing to the rubbers in the usual way. Should it be desirable to make coarser work and only use three spools, one doffing-roller can be dispensed with by putting fifty-four divisions or rings on the doffer and making the collars on

the doffing-rollers to suit the width of the rings on the doffer. The fiber-separator must also be adjusted to suit the rings on the doffer. The doffing-rollers and fiber-separator can be adjusted to suit any kind of work, coarse or fine, with two spools or more. At those points on the doffer where the fiber-separator separates the wire the doffer will not take the fibers from the cylinder. To remedy this and prevent the fibers from collecting at any part of the cylinder, I cause the doffer to traverse the face of the cylinder.

In Fig. 2 it will be seen that the doffer fiber-separator and doffing-rollers are all connected or hung on the doffer-shaft by the plate R. On the end of the doffer-shaft, Fig. 2, is the traversing-cam E, (more plainly seen in Fig. 3.) The stand F is firmly fixed to the card-frame,

and as the doffer revolves the cam E causes the doffer to traverse the face-cylinder for the above-described purpose.

I claim—

1. The revolving toothed cylinder I, in combination with the doffing-cylinder B of a condensing carding-engine, as forming a fiber-separator, as described in my specification.

2. The stripper S, in combination with the revolving toothed cylinder I, for the purpose of removing the fibers which may collect on the teeth and carrying them back to the main cylinder, as described in my specification.

ISAAC STEAD.
